ELECTRIC BELL

Lewis J. Stern, Adrian, Mich., assignor, by mesne assignments, to Schwarze Electric Company, Chicago, Ill., a limited partnership of Illinois

Application October 2, 1941, Serial No. 413,267

7 Claims.

(Cl. 177—7)

This invention relates to electric bells and has for its object to provide a simple and reliable bell structure which may be manufactured and assembled at low cost.

A further object is the provision of a novel type of bell for alternating current operation. Other objects will appear in the following description.

A preferred embodiment of the invention described herein relates to an alternating current bell of the contactless type. Known bells of this kind fall into two general groups, namely, plunger type bells and polarized bells.

The bells of the plunger class usually consist of an electro-magnetic system, such as a solenoid. In this type of bell the plunger or the armature is held out of the magnetic field by a spring of sufficient strength to give the armature or plunger a natural period of 120 cycles per second or greater. In this type of mechanism when an electromotive force of 60 cycles per second is applied to the winding the armature or plunger will respond and pull into the field during half of each cycle or in other words, will attempt to vibrate at 120 strokes per second. This synchronization of vibration with the applied E. M. F. will, of course, only be true when the plunger or armature is vibrating freely and not striking against the gong. When it strikes against the gong its natural period will be interfered with and the actual rate of vibration will be determined by the resultant of all the forces at play consisting largely of the spring tending to pull the armature out of the magnetic field, the natural frequency of the gong, and the working friction of the parts, all of which operate in the reverse direction from the magnetomotive force generated by the applied alternating current.

It will be readily seen that the value of the magnetomotive force necessary to operate a system of a given mass at 120 cycles per second will be considerably more than the sum total of the restraining forces. The restraining force consisting of the pull generated by the spring will be quite large owing to the fact that this force must be of sufficient value to give the vibrating system a natural frequency of at least 120 cycles per second.

For this reason bells constructed to operate under this principle require a large power input and in order to develop sufficient magnetomotive force to operate without the generation of too much heat must be made with large electro-magnetic systems. It is for this reason that this type of bell is only commercially satisfactory in

the larger sizes for direct operation on power circuits. Where this type of bell is used on transformer circuits the transformer capacity required is so large that their use is not recommended.

The electromagnetic system of the polarized bell is substantially the same as that given in the description above but since this bell has to operate at a frequency of only 60 cycles per second instead of 120 cycles per second the spring required to generate the returning force of the solenoid or armature to which the plunger is attached is very much smaller and therefore the power input is greatly reduced.

15 In addition to the electromagnetic system there is, at present, in the polarized mechanism a permanent magnet, the poles of which are arranged to set up a unidirectional magnetomotive force in the plunger in the case of solenoids, and in the electromagnets themselves where that type of construction is used.

20 During one-half of the cycle the magnetomotive force generated by the applied alternating current will be in the same direction as the magnetomotive force generated by the permanent magnet and in the other half of the cycle it will be in the opposite direction so that the net result will be a magnetomotive force equal to the sum of that caused by the permanent magnet and that generated by the coil windings and during the other half of the cycle it will be equal to the difference between these values. In order to get the maximum net value of this difference the design is usually such that the magnetomotive force generated by the applied alternating current is as near as possible to the maximum which can safely be used without tending to de-magnetize the permanent magnet. It will be apparent that if the magnetomotive force generated by the electromagnet is too large in value the magnetization of the permanent magnet will be reduced and will result in a diminution of the bell intensity.

25 30 35 40 45 50 55 For the reason given above the volume obtainable from a polarized bell is limited to the amount of magnetomotive force that can be generated electrically without tending to de-magnetize the permanent magnet. For this reason it will be readily seen that the possible force with which a gong can be struck is considerably less than in the type of mechanism first described. Another disadvantage present in this type of construction is that permanent magnets tend to lose their magnetism over a period of years and are also affected in some measure by shock

due to rough handling possible during shipment or installation.

The good features of both the mechanisms heretofore described are taken advantage of in the present invention where a rectifier is used to replace the permanent magnet present in polarized bells, or added to the plunger type.

With this arrangement the armature or plunger is only required to operate at a natural frequency of 60 cycles per second and therefore the restraining force of the spring can be as small as that in the polarized bell but the power input is limited only by the size of the rectifier and winding employed. This rectifier is placed in series with the coil windings and when an alternating current is applied to the system the current flowing through the winding consists of an intermittent half wave with a 60 cycle frequency.

When it is realized that at least 50% of the power input of a polarized bell is being employed merely to reverse the magnetic effect of the permanent magnet and results only in heat losses, it will be immediately apparent that the same amount of power input with the rectifier type of bell will approach twice the intensity of sound, owing to the fact that in order to obtain the same power input the current flowing must be approximately double that of the polarized bell, for the reason that the current flows during only one-half the cycle. This statement, of course, does not take into account the efficiency of the rectifier nor does it take into account the slight backward leakage through the rectifier, but it does give a theoretical explanation of the difference between the two types of bells.

The present invention contemplates a bell of the solenoid type for the reason that only one moving part is required and the construction is thus made as simple as possible. It is realized that the efficiency of a solenoid is materially less than that of a laminated core construction with a movable armature, but the advantages gained by using a selenium rectifier are so great that the bell as a whole is much more efficient than the best type of polarized construction heretofore employed. The use of a solenoid in conjunction with a selenium rectifier permits enough reduction in size of the electromagnetic system to allow a design where a bell 6-inches and upward can be fastened to the cover of an outlet box by a single screw passing through the center of the bell. The novel adapter plate which fits on almost any outlet box is usable for all sizes of bells, and it is possible for the user to install and wire these plates on outlet boxes while a construction job is going on, installing the proper bells later. The subsequent installation of the bells is so simple that the services of a journeyman electrician are not required in any jurisdiction for this type of work.

The invention will now be described with the aid of the accompanying drawings, of which—

Fig. 1 is a plan view of a bell enclosed by a guard, according to the present invention;

Fig. 2 is a circuit diagram;

Fig. 3 is a plan view of the bell with the casting removed;

Fig. 4 is a vertical section taken through 4—4 of Fig. 3, but somewhat reduced in scale;

Fig. 5 is a detail showing the connection of the bridge to the base.

In a preferred embodiment of the invention, the bell consists of a disc shaped base plate 10, Fig. 4, provided with a pair of spaced bosses 11, Fig. 5, each having an opening through which a

stud 12 extends. The studs are each provided with a collar 13 which may be spot welded to the under side of the base plate and a threaded part 14 depending therefrom. Feet 15 of bridge 5 have openings through which the studs pass, and nuts 17 secure the bridge to the tops of the bosses.

The top of the bridge has a flattened part 18 having in its mid-section an opening 19 under which and in alignment therewith is secured by suitable means, a nut 20. A casing 25 having a flat axially disposed top section 26 which rests on the part 18 of the bridge is provided with a cylindrical wall portion 27 flanged at 28 to overlie the base plate, the flange being turned down at 29 to overlap the edge of the base and prevent any motion of the base and casing in respect to each other. A suitable gasket 30 may be placed between flange 28 and base plate 10.

20 A gong 31 is concentrically secured to the casing by means of an eyelet 32 disposed in openings in the gong and casing. A hollow screw 33 having a hexagonal head 34 extends through the eyelet and screws into nut 29 to hold the flattened part of the top part 18 of the bridge and also to press the flange 29 against gasket 30 and base plate 10, so thus by a single screw the whole structure is held together. A washer 35, cut away on its under surface at 36 so as to clear the eyelet and distribute pressure is placed on the screw between the head thereof and the upper surface of the gong.

30 Solenoid winding 40 is supported between angle plates 41 and 42 secured to the base. Angle plate 41 also supports selenium rectifier 43 by means of arm 44 fastened thereto.

35 A brass tube 45 extends through the solenoid. One end of the tube is closed by stop screw 46 while the opposite end is turned over at 47. A plunger 48 is disposed in the tube and is normally held back against stop screw 46 by spring 49 disposed on the neck 50 of the plunger which extends outwardly from the end of the tube. The open end of the tube projects through an opening in the wall of the casing so that when the plunger is reciprocated, the end of the neck thereof will strike the depending surface of the gong.

40 An opening in base plate 10 is covered by a connecting block 55 of molded insulating material fastened to the base by screws and nuts 56. The block is formed to cover as well as fill the opening in the base plate. Two openings 57 are provided therein from each of which a sturdy metal bar 58 projects. The upper part of bars 58 are turned over so as to fit in recesses formed in the upper surface of the connecting block substantially parallel to the base where they are securely held by nuts 60 and bolts 61 molded into the connecting block. This arrangement provides binding posts as well as external connecting means to which the bell circuit consisting of the solenoid connected in series with the rectifier are attached. Bars 58 and the circuits therefore are further separated and protected by an upwardly projecting part 62 of the connector block which is higher than the tops of bolts 61.

45 Bars 58 are arranged to fit into spring connecting clips held by a terminal block secured to the underside of a cover plate of novel construction adapted to fit outlet boxes of the kind in general use.

50 A preferred embodiment of a cover plate according to the present invention consists of a metal disc 70 provided on its upper surface ad-

jacent to the edge thereof with a concentric ridge 71 arranged to engage the under surface of base plate 10, the ridge being sufficiently high so that parts depending from base plate 10, particularly the ends 14 of studs 12 are held clear of the surface of the cover plate. A boss 72, corresponding in height to ridge 71 has a nut 73 secured to the under side thereof. A screw 74 extending through hollow screw 33 and through base plate 10 is held by nut 73 of the cover plate. With this arrangement the bell is secured to the cover plate by a single screw. A groove 75 in the body of the screw retains a loosely fitting spring ring 76 which prevents screw 74 from being entirely withdrawn from screw 33. With this arrangement, the person installing the bell has only one part to handle.

Cover plate 70 is provided with an opening which is covered by a molded terminal block secured to the under side of the plate. The opening is disposed to be in register with the corresponding opening for the terminal block 55 on base plate 10. The molded part of terminal block 80 is identical with bell terminal block 55. Block 80, however, has a sturdy brass strip 81 secured by a nut 82 and a bolt 83 in each of two channels formed in the blocks. The brass strips are formed into U-shaped clips 84 registering with the lower ends of openings formed in the block communicating with the upper surface thereof to receive the connecting bars 58 of the bell which when inserted into the channels spread the clips which exert sufficient pressure on the bars to support the bell securely by this means alone, notwithstanding the fact that the single screw arrangement described above is also provided as a support.

Power wires may be attached by means of nuts 86 on bolts 83 to clips 84.

A protecting cover 87 of insulating material is pivoted to the terminal block at 88. The cover is normally held in position over terminal bolts 83 by a small point 88 (shown on the corresponding part of terminal block 55, Fig. 3), formed on the terminal block which enters a hole, not shown, in cover 87. When access to the connector members is required the cover may be turned on its pivot as indicated in the drawings by dotted lines. With this arrangement cover plate 70 cannot be secured to the outlet box until cover 87 is restored to its normal position.

Cover plate 70 may be provided with a plurality of differently spaced hole arrangements for fastening the plate to various kinds of outlet boxes. In Fig. 4 screws 90 are shown attaching the cover plate to outlet box 91.

The bell structure just described may be readily changed to a guarded bell by means of a disc shaped plate 92 of greater diameter than base plate 10 provided with a plurality of openings which clear projections depending from the under side of base plate 10 so the surfaces of plates 92 and 10 may be placed in uniform contact with each other. Two of the openings in plate 92 are disposed to receive threaded members 14 of stud 12, Fig. 5, permitting the plates to be secured to each other in concentric relation by nuts 93 on said threaded members. A dome-like guard member 94, Figs. 1 and 4, provided with a flat surface 95 adjacent to the edge thereof, to which are welded a number of screws 96 that register with holes in plate 92 is secured to the plate by nuts 97. The edge of the part 95 is turned over at 98 to overlap the edge of disc 92. The guard member is slotted at 99 in the

lower half thereof and an opening 100 is provided in the top thereof to permit access to screw 74 by which the entire structure may be fastened to an outlet box.

5. The cover plate is secured to the outlet box so that the slotted part of the guard is in the lowermost position, thus furnishing additional protection to the bell from the elements.

While but one embodiment of the invention 10 has been disclosed, it will be understood that numerous modifications of the same may be made by those skilled in the art without departing from the spirit and scope of the invention.

What is claimed is:

15. 1. In an electric bell, a base member, a bridge secured to said base member, a casing having a top portion and a depending wall portion overlying said bridge said wall portion being adapted to engage said base member and to cooperate therewith to enclose completely the working parts of said bell to protect said parts from dust and moisture, electro-magnetic gong operating means including a striker supported by said base member within said casing, a gong disposed over said casing and secured thereto by a single eyelet, an opening in said casing through which said striker can strike said gong and screw means passing through said eyelet for securing said gong and said casing to said bridge.
20. 2. In an electric bell, a base member, a bridge secured to said base member, a casing having a top portion and a cylinder shaped wall portion disposed on said base member overlying said bridge, a gong concentrically disposed on the outside of said casing having edges depending below the top portion thereof, a single eyelet for securing said gong to the top portion of said casing, threaded means at the top of said bridge, means comprising a single screw device cooperating with said threaded means for securing said gong and said casing to said bridge urging the wall portion of the latter against the surface of said base member, and electro-magnetic gong operating means including a striker supported by said base member within said casing and an opening in said casing through which said striker can strike said gong.
25. 3. An electric bell according to claim 1 in which said screw means is a hollow screw, single screw means for supporting said bell comprising a screw extending through said hollow screw having a threaded portion extending through said base member, said threaded portion being adapted to screw into a nut secured to a supporting device.
30. 4. An electric bell according to claim 1 having a terminal block secured to the upper surface of said base member, a pair of metal strips adapted to cooperate with a detachable connector device secured to said terminal block, said strips being formed so as to extend from said terminal block through said base member and project from the under side thereof substantially at right angles thereto.
35. 5. An electric bell according to claim 1 in which a pair of upwardly extending bosses are formed in said base member, a hole through each boss, a threaded member having a collar in substantially the midportion thereof projecting upward through each of said holes, the collar portion of each threaded member being disposed within the respective bosses, means for securing the bridge to the portion of the threaded members projecting through said bosses thereby securing said threaded members to said base member, and means to secure the base of a guard member to

the opposite end portions of said threaded members.

6. An electric bell according to claim 1 wherein in said casing comprises a cylindrical wall portion, a flange formed at the edge of said wall portion adapted to overlie the upper surface of the base member, and a turned over edge on said flange arranged to fit over the edge of said base member.

7. An electric bell according to claim 1 where-

in said casing comprises a cylindrical wall portion, a flange formed at the edge of said wall portion adapted to overlie the upper surface of the base member, a turned over edge on said flange arranged to fit over the edge of said base member, a ring-shaped gasket disposed between said flange and said base member held in tight engagement therewith by said single screw device.

LEWIS J. STERN.
